UNITED STATES PATENT OFFICE.

EDWIN E. ANGELL, OF MALDEN, MASSACHUSETTS.

DESIGN FOR A SEWING-MACHINE ARM.

SPECIFICATION forming part of Design No. 16,862, dated August 24, 1886.

Application filed July 20, 1886. Serial No. 208,562. Term of patent 7 years.

To all whom it may concern:

Be it known that I, EDWIN E. ANGELL, of Malden, in the county of Middlesex and State of Massachusetts, have invented and produced 5 a new and original Design for the Arms of Sewing-Machines, of which the following, taken in connection with the accompanying drawing, is a specification.

The drawing represents in side elevation a 10 sewing-machine embodying my design.

The leading feature of my design is the open-work overhanging arm A, having vertical and horizontal portions, with open spaces, which are ornamented by irregular cross-bars formed 15 in the shape of letters and joined to the opposite rims or sides of the said spaces.

B is the base of the frame, said base having, 20 in the form herein shown, two forwardly-projecting arms; but the form of the said base or the shape and number of the ornamental let-

ter cross-bars for the spaces or open-work panels of the arm A may be varied without departing from the leading feature of my design.

I claim—

The design for a sewing-machine arm herein shown and described, the same consisting of the right-angular arm with vertical and horizontal portions, having open spaces ornamented by irregular cross-bars in the form of 25 letters, as set forth.

In testimony whereof I have signed my name to this specification, in the presence of two subscribing witnesses, on this 12th day of July, A. D. 1886.

EDWIN E. ANGELL.

Witnesses:

A. H. SPENCER,
ELIHU G. LOOMIS.
